UNITED STATES PATENT OFFICE.

CHARLES WILLIAM RIPSCH AND JAMES C. DAWLEY, OF DAYTON, OHIO, ASSIGNEES
TO THE JOYCE-CRIDLAND COMPANY, OF DAYTON, OHIO, A CORPORATION OF OHIO.

SELF-LOWERING JACK.

Application filed June 27, 1921. Serial No. 480,540.

To all whom it may concern:

Be it known that we, CHARLES W. RIPSCH and JAMES C. DAWLEY, citizens of the United States, residing at Dayton, in the county of 5 Montgomery and State of Ohio, have invented certain new and useful Improvements in Self-Lowering Jacks, of which the following is a specification, reference being had therein to the accompanying drawing.

10 This invention relates to self lowering jacks for car journal boxes and the like.

One object of the invention is to provide a jack which may be suspended from a car journal, or other fixed support, with its lifting element beneath the part to be lifted, and in which the lifting element may be moved downwardly by the weight of the load and such downward movement controlled by the operator.

20 Another object of the invention is to provide a self lowering jack in which the power multiplying devices employed for raising the load may be utilized as retarding devices, on the downward movement of the 25 lifting element, which will reduce the power transmitted from the lifting element to the controlling device.

A further object of the invention is to provide a jack of this kind which will be simple in its construction and of a strong durable character.

Other objects of the invention will appear as the device is described in detail.

In the accompanying drawings Fig. 1 is 35 a side elevation, partly broken away, of a jack embodying my invention, the journal box being shown in section; Fig. 2 is a top plan view, partly in section, of the lower end of the jack; Fig. 3 is a side elevation 40 of the lower end of the jack, partly in section; Fig. 4 is a section taken on the line 4-4 of Fig. 3; Fig. 5 is a transverse sectional view taken through the brake drum forming part of the controlling device; Fig. 45 6 is a side elevation of the lower portion of the jack, partly in section, showing a modified form of controlling device; Fig. 7 is a section taken on the line 7-7 of Fig. 6; Fig. 8 is a side elevation of the lower portion 50 of a jack, partly in section, showing another form of controlling device; Fig. 9 is a sectional view taken on the line 9-9 of Fig. 8; Fig. 10 is a side elevation of the lower portion of the jack, partly in section, show-

ing another modification of the controlling device; Fig. 11 is a section taken on the line 11-11 of Fig. 10; and Fig. 12 is a plan view, partly in section, on the line 12-12 of Fig. 10.

In these drawings we have illustrated one embodiment of our invention, with certain modifications thereof, and have shown the same as applied to a car journal box jack of the type shown and described in Patent No. 1,369,432 granted February 22, 1921 to John A. Hope, but it will be understood that this particular type of jack has been shown for the purposes of illustration only and that the invention may be applied to jacks of various kinds and may take various forms without departing from the spirit thereof.

In that form of the device here shown the jack comprises a supporting frame 1 which is shown as substantially C-shaped and has its upper end adapted to be supported by the car journal, which is shown at 2. The end of the jack frame 1 is shown as extending through the open end of the journal box 3 and as connected with a supporting device 4 which engages the flanged end of the journal and forms a fulcrum point for the jack frame. The lower portion of the frame carries a lifting element adapted to engage beneath the journal box, or other part to be elevated, and is here shown as comprising a screw threaded shank 5 having a head 6 to engage the load. In the present instance, the screw does not rotate but is screw threaded into a nut 7 which is journaled in a suitable bearing 8 in the lower portion of the jack frame and this nut is rotated to impart vertical or lifting movement to the lifting element. Rigidly secured to the nut is a worm wheel 9 meshing with a worm 10 carried by a shaft 11 extending transversely through the frame 1 and journaled in that frame at the opposite ends of the worm. The shaft may be operated, to rotate the worm, in any suitable manner but in the present instance it is ratchet operated and we have shown the shaft as projecting beyond one side of the frame and having secured thereto a ratchet wheel 12, which in the form shown has relatively small V-shaped teeth. Cooperating with this ratchet wheel is a reversible dog, or pawl, here shown in the form of a bar 13 mounted for

sliding movement in a guideway 14 formed in a lever socket 15, which is adapted to receive the operating lever 16. The guideway 14 is arranged substantially in the plane of the ratchet wheel and the pawl 13 is provided with two sets of teeth, 17 and 18, adapted to be moved into and out of engagement with the teeth of the ratchet wheel when the pawl is moved from one position to the other. These two sets of teeth are separated by a recess 19 and their arrangement is such as to give the pawl substantially a double wedge shape. The pawl is held in its adjusted positions by means of a spring-pressed detent 20 mounted in the lever socket and adapted to engage either one of three notches 21, thus serving to hold either set of teeth in engagement with the ratchet wheel or to hold the pawl in an intermediate or neutral position. As shown in Fig. 1, the pawl is in operative position for lifting the load and upon the upward movement of the lever the detent 20 will yield sufficiently to permit the lower set of teeth 17 to ride over the teeth of the ratchet wheel but upon the downward movement of the lever the pawl will be gripped between the ratchet wheel and the wall of the guideway with a wedging action so as to firmly connect the lever with the ratchet wheel and thus actuate the lifting mechanism. To lower the load by means of the lever the pawl is reversed so that the upper set of teeth 18 will operatively engage the ratchet wheel upon the upward movement of the lever, thus operating the lifting mechanism in a reverse direction and lowering the load. The shaft 11 is also provided with a hand wheel, or knob, 22, by means of which the lifting element can be adjusted when the pawl is in its neutral position and there is no load on the lifting element. In order to facilitate and expedite the lowering of the load it is desirable that the mechanism should be of such a character that the lifting element will, when unrestrained, move downward under the weight of the load and that means be provided for controlling this downward movement of the lifting element. To accomplish this we have so arranged the pitch of the threads on the shank of the lifting element and in the nut that the weight of the load will impart movement to the nut and, consequently, to the worm wheel carried thereby, and we have also provided the worm wheel and the worm with spirals of such a pitch that the rotation of the worm wheel will serve to rotate the worm, thereby permitting the lifting mechanism to be rotated in a reverse direction by the weight of the load. To control this downward movement of the lifting element we have mounted on the worm shaft 11, on that side of the frame opposite the ratchet wheel 12, a suitable controlling device which

will serve to retard the movement of the load to such an extent as to place the same absolutely under the control of the operator. By utilizing the power multiplying devices of the lifting mechanism to transmit the movement from the load to the controlling device, as the load moves downward, we are enabled to employ a controlling device which requires but little power for its operation and which will easily hold an extremely heavy load against downward movement. This is due to the fact that the thrust of the load is to a large extent absorbed by the frictional contact between the screw threaded shank of the lifting element and the nut and between the worm and the worm wheel. The controlling device may take various forms but as shown in Figs. 2 to 5, it comprises a brake drum, preferably in the form of a disk 23, mounted on the end of the shaft 11 and adapted to rotate with that shaft when the load is lowered. Cooperating with the brake drum is a second brake member which preferably consists of two shoes 24 pivoted at 25, on one side of the drum, and having at their ends, on the opposite side of the drum, means for actuating the same. We prefer that the brake shoes should be normally set, that is, held in operative frictional contact with the brake drum and to this end the brake shoes 24 are shown as provided with parallel portions, or arms 26 extending outwardly therefrom and having openings through which extends a rod or a bolt 27 about which is coiled a spring 28, this spring being confined between one of the arms 26 and a nut 29 on the end of the bolt, and thereby tending to move the brake shoes one toward the other and causing them to exert pressure on the brake drum. To release the brake and permit the load to move downward the arms 26 are separated and this is accomplished in the present device by means of a stud 30 journaled in one wall of the casing 31 which encloses the controlling device and having its inner portion extending between the two arms 26 of the brake shoes and flattened as shown at 32, the flattened portion being arranged to lie normally parallel with the arms of the brake shoes. Consequently, when the stud is rotated it will engage the arms with a cam action and spread them apart, thereby permitting the frictional resistance to the rotation of the worm shaft to be wholly or partly removed. The stud is here shown as provided with an operating handle 33 arranged outside of the casing 31. Inasmuch as the brake is normally set it is necessary that some means be provided for disconnecting the brake from the worm shaft when the latter is operated in a direction to raise the load and we have, therefore, shown the brake drum 23 as mounted on the shaft in such a manner that it will be connected

therewith only when the shaft is rotated in a direction to lower the load. Preferably, this is accomplished by interposing a one way clutch between the brake drum and the shaft. As shown in Figs. 4 and 5, the brake drum is rotatably mounted on a disk 34 rigidly secured to the shaft 11 and having in its periphery a series of tapered recesses 35 in each of which is arranged a roller 36 which is acted upon by a spring pressed plunger 37 tending to move the roller toward the small end of the tapered recess. The recesses are so arranged that when the shaft is rotated in a direction to elevate the lifting element the rollers will be moved toward the larger ends of the recesses and the shaft disconnected from the brake drum so that it can rotate freely therein in that direction. When the shaft is rotated in the opposite direction, by the lowering of the load, the rollers will be moved toward the small ends of the recesses and will rigidly connect the shaft with the brake drum.

The clutch connection between the brake drum and the shaft 11 may take various forms and, as shown in Fig. 7, the brake drum 38 is provided with flanges 39 at its inner and outer edges which engage shoulders, or recesses, 40, on the respective sides of the disk 41, which is rigidly secured to the shaft 11. The intermediate portion of the brake drum is provided with ratchet teeth 42 with which cooperate a plurality of spring pressed pawls 43 mounted in the disk and extending radially thereof, the pawls being so arranged that they will ride over the teeth when the shaft rotates in a direction to elevate the load and will engage the teeth when the shaft rotates in the opposite direction.

In Figs. 8 and 9 we have shown still another form of the clutch mechanism. In this instance a brake drum 44 is mounted directly on the shaft 11 and the end of the shaft extends beyond the brake drum and has rigidly secured thereto a disk 45. The brake drum is provided on its outer surface with ratchet teeth 46 with which cooperate spring pressed pawls 47 mounted in the disk 45 and arranged parallel with the axis thereof. In both the forms shown in Figs. 6 and 7 and the form shown in Figs. 8 and 9, the brake shoes 26 are of the same construction and are operated in the same manner as they are in the form shown in Figs. 2 to 5.

In Figs. 10 to 12 we have substituted for the brake a pawl and ratchet controlling device and as there shown, a ratchet wheel 48 is rigidly secured to the end of the shaft 11 and a pawl 49 is pivotally mounted adjacent to the ratchet wheel and is provided with an operating arm 50, extending about the ratchet wheel and projecting through an opening in the casing, where it is provided with a handle 51. A spring 52 acts

on the handle portion of the arm to hold the pawl normally in engagement with the ratchet wheel, in which position it will prevent the rotation of the worm in a direction to lower the load. When the load is to be lowered the arm 50 is operated to disengage the dog from the ratchet wheel but as soon as released the dog will automatically engage the ratchet wheel and check the movement of the load.

The operation of the device will be readily understood from the foregoing description and it will be apparent that we have provided a self-lowering jack of this kind in which the load will move downwardly by gravity but will be at all times under the perfect control of the operator. By utilizing the power multiplying devices of the lifting mechanism to transmit the movement from the downwardly moving lifting element to the controlling device we reduce the power as applied to the controlling device to such an extent that the latter can be very easily controlled and a relatively light frictional contact will check the movement of a very heavy load. Further, by utilizing the lifting mechanism for this purpose the device is simplified and the necessity of providing additional mechanism is avoided.

While we have shown and described certain embodiments of our invention we wish it to be understood that we do not desire to be limited to the details thereof as various modifications may occur to a person skilled in the art.

Having now fully described our invention what we claim as new and desire to secure by Letters Patent is:

1. In a lifting jack, a frame adapted to be suspended from a car journal, a lifting element carried by said frame and adapted to extend beneath the load to be lifted, means to actuate said lifting element to elevate the load, said lifting element being of such a character that when unrestrained it will move downward under the weight of the load, and manually operable means for controlling the downward movement of said lifting element.

2. In a lifting element, a frame adapted to be suspended from a car journal, a lifting element carried by said frame and adapted to extend beneath the load to be lifted and when unrestrained to be moved downward by the weight of the load, an actuating device for said lifting element, power multiplying devices interposed between said actuating device and said lifting element and so constructed and arranged that they will be moved in a reverse direction by the downward movement of said lifting element, and manually operable means to control said reverse movement of said power multiplying devices.

3. In a lifting element, a frame adapted

1 to be suspended from a car journal, a lifting element carried by said frame and adapted to extend beneath the load to be lifted and when unrestrained to be moved downward by the weight of the load, an actuating device for said lifting element, power multiplying devices interposed between said actuating device and said lifting element and so constructed and arranged that they will be moved in a reverse direction by the downward movement of said lifting element, and a manually controlled brake connected with said power multiplying devices to control their movement in a reverse direction.

15 4. In a lifting element, a frame adapted to be suspended from a car journal, a lifting element carried by said frame and adapted to extend beneath the load to be lifted and when unrestrained to be moved downward by the weight of the load, an actuating device for said lifting element, power multiplying devices interposed between said actuating device and said lifting element and so constructed and arranged that they will be moved in a reverse direction by the downward movement of said lifting element, a brake drum, means for connecting said brake drum with said power multiplying devices only when the latter are moved in a reverse direction, and a manually controlled friction element acting on said brake drum to retard its movement.

30 5. In a lifting jack, a frame adapted to be suspended from a car journal, a lifting element carried by said frame and adapted to extend beneath the load to be lifted, means to actuate said lifting element to elevate the load, said lifting element being of such a character that when unrestrained it will move downward under the weight of the load, a worm wheel, means actuated by the downward movement of said lifting element to rotate said worm wheel, a worm meshing with said worm wheel and adapted to be rotated thereby, a rotatable member, means for connecting said rotatable member with said worm when the latter is rotated by said worm wheel, and manually operable means for controlling the rotation of said rotatable member by said worm.

35 6. In a lifting jack, a frame adapted to be suspended from a car journal, a lifting element carried by said frame and adapted to extend beneath the load to be lifted, means to actuate said lifting element to elevate the load, said lifting element being of such a character that when unrestrained it will move downward under the weight of the load, a worm wheel, means actuated by the downward movement of said lifting element to rotate said worm wheel, a worm meshing with said worm wheel and adapted to be rotated thereby, a rotatable member, a one way clutch connecting said rotatable member with said worm, and manually operable

means to control the rotation of said rotatable member.

7. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said nut, a worm wheel connected with said nut, a worm meshing with said worm wheel and adapted to be rotated thereby, means for actuating said worm to impart upward movement to said lifting element, and a device connected with said worm to control its movement by said worm wheel.

8. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said nut, a worm wheel connected with said nut, a worm meshing with said worm wheel and adapted to be rotated thereby, means for actuating said worm to impart upward movement to said lifting element, a brake member, means for causing said brake member to be actuated by said worm only when the latter is rotated by said worm wheel, and a second brake member cooperating with the first brake member to control the rotation of said worm by said worm wheel.

9. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said nut, a worm wheel connected with said nut, a worm meshing with said worm wheel and adapted to be rotated thereby, means for actuating said worm to impart upward movement to said lifting element, a shaft connected with said worm wheel, a brake member rotatably mounted on said shaft, means to connect said brake member with said shaft when said worm is rotated by the downward movement of said lifting element, and a second brake member cooperating with the first mentioned brake member to control the rotation of said worm.

10. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said

- nut, a worm wheel connected with said nut, a worm meshing with said worm wheel and adapted to be rotated thereby, means for actuating said worm to impart upward movement to said lifting element, a shaft connected with said worm, a disk rotatably secured to said shaft, a brake drum rotatable about the axis of said shaft, and a one-way clutch to connect said brake drum with said disk when said shaft is rotated by the downward movement of said lifting element.
11. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said nut, a worm wheel connected with said nut, a worm meshing with said worm wheel and adapted to be rotated thereby, means for actuating said worm to impart upward movement to said lifting element, a shaft connected with said worm, a disk rigidly secured to said shaft, a brake drum rotatably mounted on said disk, a one way clutch interposed between said brake drum and said disk to cause the drum to rotate with the disk when the latter is rotated by the downward movement of said lifting element, and a brake member cooperating with said brake drum.
12. In a lifting jack, a frame, a lifting element mounted on said frame, means for imparting lifting movement to said lifting element, a worm wheel so connected with said lifting element that it will be rotated by the downward movement of said lifting element, a worm meshing with said worm wheel and adapted to be rotated thereby, a shaft connected with said worm, a brake

drum rotatably mounted about the axis of said shaft, a one way clutch to connect said brake drum with said shaft when the latter rotates in one direction and a brake member cooperating with said brake drum. 45

13. In a lifting jack, a frame, a lifting member carried by said frame, a worm wheel connected with said lifting element to impart lifting movement thereto and to be rotated thereby when said lifting element moves downwardly, a worm meshing with said worm wheel and adapted to be rotated thereby, means for rotating said worm in a direction to impart lifting movement to said lifting element, a brake drum, a clutch connection between said brake drum and said worm to cause said drum to rotate with said worm when the latter is actuated by said worm wheel, and a brake member cooperating with said brake drum. 50 55 60

14. In a lifting jack, a frame, a lifting element carried by said frame and having a screw threaded portion, a nut rotatably mounted in said frame to receive said threaded portion of said lifting element, the threads of said lifting element and said nut having such a pitch that the downward thrust of said lifting element will rotate said nut, a worm wheel connected with said nut, a worm meshing with said worm wheel and adapted to be rotated thereby, means for actuating said worm to impart upward movement to said lifting element, a ratchet wheel connected with said worm, a pawl held normally in engagement with said ratchet wheel, and means for disengaging said pawl from said ratchet wheel. 75 70 75

In testimony whereof, we affix our signatures hereto. 80

CHARLES WILLIAM RIPSCH.
JAMES C. DAWLEY.
